UNITED STATES PATENT OFFICE

ALFRED DROTH, OF KASSEL-WILHELMSHOHE, AND CARL VOLLMAND, OF KASSEL, GERMANY, ASSIGNORS TO THE SUPERHEATER COMPANY, OF NEW YORK, N. Y.

SUPERHEATER

Application filed May 13, 1930, Serial No. 451,962, and in Germany May 28, 1929.

This invention has for its purpose the provision of another form of a two-part superheater header of the type shown in German application #86,887. In the header according to said application the superheater elements are secured to the header in such a way that two similar ends are secured to the middle chamber of the header, these two ends belonging to two superheater elements or 10 groups arranged one in front of the other. By the term "similar ends" are meant ends both receiving saturated steam or both delivering superheated steam. In the form shown in said application it is impossible to 15 connect the ends of the elements to the header in the proper sequence where these ends are arranged in such order that the saturated and superheated ends alternate since the header has only three chambers. The present 20 invention makes such connection possible, however, while retaining the advantages of the superheater header made in two parts in accordance with said former application. In accordance with the present invention the 25 header contains four chambers which may for example be of prismatic form, of which two are connected with each other and contain saturated steam, the other two being likewise connected to each other and containing 30 superheated steam. The four chambers may be arranged one in front of another, or one above another, the saturated and superheated chambers alternating.

One pair of said chambers may have its 35 narrow sides connected by means of connecting pieces so as to form a frame-shaped structure while the other pair may have its long sides connected by means of bridging pieces. In this manner the two parts of the header 40 can readily be assembled.

The several chambers may be arranged beside one another in such a way that their lower sides, that is those sides which are to 45 serve for the connection of the superheater elements, may lie generally horizontal, or in case the chambers are arranged one above another, these surfaces may lie substantially vertical. The four surfaces may lie in the same plane, or in different planes, in the latter case presenting a stepped arrangement.

The drawings show in Figs. 1 to 10 some illustrative forms of the invention. Fig. 1 shows a steam header in vertical section; Fig. 2 shows at the right a front half-view, and at the left a half-section on line 2—2 of Fig. 3 of the form of Fig. 1; Fig. 3 shows a top plan view of the same form; Fig. 4 shows a section similar to Fig. 1 of a variation; Figs. 5 to 10 show in vertical section, side and top views two further variations.

In all forms the steam header consists of two separate parts, and each part contains two saturated steam chambers 1 and two superheated steam chambers 2 which are arranged side by side or one above the other in such a manner that saturated and superheated headers alternate. The saturated steam chambers 1 in the form according to Figs. 1 to 3 have two of their long sides connected to each other by means of the bridge piece 3, while the superheated steam chambers 2 are connected to each other at their shortest sides or ends into a rectangular frame. Steam is conveyed to the header from the boiler through connection 5 which is a continuation of the bridge piece 3. The superheated steam is carried from the superheated chambers 2 and 4 through the connections 6—6. The steam chambers in this form of the arrangement are so arranged 75 side by side that their undersides, that is to say the surfaces to which the ends of the superheater elements are attached, lie in a horizontal plane. In this header the last chamber at the right is a superheated chamber, whereas in the form according to Fig. 4, the last chamber at the right is a saturated chamber. Except for this difference the form of the header according to Fig. 4 is similar to that shown in Figs. 1 to 3, the

saturated chambers 1 being in each case connected at their long sides by means of the bridge piece 3, while the superheated chambers 2 are connected at their shortest sides into a frame by the connecting pieces 4. Instead of having a single connecting bridge 3 between two similar chambers there might evidently be two or more, or the chambers might be connected along their entire length by means of a bridge piece. As is

evident from Figs. 1 to 3, the two parts of the header consisting respectively of the two chambers 1 and the bridging piece 3 and of the two chambers 2 and the connecting pieces 5 4 can easily be assembled into the complete header, one part being inserted into the other.

In the variations shown in Figs. 5 to 10 the pairs of chambers 1 and 2 are arranged 10 vertically in alternating relation, the front faces, which form the surface to which the superheater element ends 7 are to be connected, lying vertically. In the form shown in vertical section in Fig. 5 the front or 15 connecting surfaces of the four chambers 1 and 2 all lie in the same vertical plane so that the ends of the superheater elements 7 and whatever means are used to secure them are readily accessible. In the form according 20 to Figs. 6, 7, 8 and 9, of which 6 and 7 are side elevations, and 8 and 9 are front views, the front or connecting surfaces of the several chambers are arranged in different 25 planes so that a stepped arrangement of the front surface and lower sides results. The ends of the superheater elements 7 can be attached either to the front sides or to the lower sides of the several chambers. The two 30 forms according to Figs. 6 and 7, and 8 and 9 respectively, differ only in the sequence of the several chambers. In Fig. 6 a superheated chamber 2 is found at the top, while in Fig. 8 a saturated chamber 1 is found in 35 this location.

Fig. 10 shows a further variation in which the front surface of the upper three chambers lie on a common vertical plane, whereas the front surface of the lowest chamber lies in a different vertical plane so that there is 40 here also a stepped form of header. The lower chamber 2 could have the ends of the elements 7 connected either to its front or to its lower side.

We claim:

1. A steam superheater header comprising in combination two separate parts each including parallel chambers, means uniting the chambers of each part, the two parts being 50 positioned relatively to each other so that the chambers of one alternate with those of the other and with their front faces disposed in different planes.

2. A steam superheater header in accordance with claim 1 characterized in that the front and lower faces of the parts present a stepped contour.

3. A steam superheater header according to claim 1 wherein a chamber of one of the 60 parts extends forward beyond a chamber of the other part.

4. A steam superheater header according to claim 1 further characterized in that a chamber of one of the parts extends forward 65 beyond a chamber of the other part and a

chamber of one part overhangs another chamber thereof.

5. A steam superheater header comprising in combination two separate parts each including two chambers, one of the parts being substantially in the form of a loop into which a chamber of the other part extends, the part of said last mentioned chamber being removably associated with the chambers of said loop. 70

6. A steam superheater header comprising in combination two separate parts each including several interconnected chambers, one of the parts being substantially in the form of a loop for straddling a chambered portion 80 of the other part. 85

7. A steam superheater header comprising in combination two separate parts each including interconnected chambers, one of the parts being substantially in the form of a loop, the other part having chambered portions straddling a chamber of the loop and removably associated therewith. 95

8. A steam superheater header of the type described, comprising in combination two separate parts each including two parallel chambers, the two parts being separably associated and so positioned relatively to each other that the chambers of one alternate with those of the other, the means uniting the two chambers of one part into one piece being a conduit bridging over the intervening chamber of the other part, and the means uniting the two chambers of the second part into one piece being two conduits extending 100 around the ends of the intervening chamber of the first part. 105
